UNITED STATES PATENT OFFICE

2,472,738

TERMINAL BLOCK

Christian B. Backer, Ottawa, Ontario, Canada

Application December 4, 1944, Serial No. 566,464
In Canada December 9, 1943

1 Claim. (Cl. 173—328)

1

This invention relates to electric heating plates such as are used in domestic kitchen ranges and the like, and more particularly to that type of range plate which employs a heating element comprising one or more tubular members.

In the design of a range element utilizing tubular members, the arrangement of the terminals thereof has always presented many problems. In some instances, the ends of the tubes are simply bent downwardly and passed through a protective sheet metal reflector plate to which the tubes may be clinched so as to make a water-tight joint and thereby prevent over-boilings from running onto the terminals. While this arrangement is a simple one, it renders quite difficult the cleaning of the reflector plate and, moreover, should one of the usual two tubular members burn out the whole element must be discarded since it is impractical to remove and replace one of the members. Another disadvantage of this arrangement is that, unless the downwardly extending ends of the tubes are very long (which often is not permissible because of lack of space), the terminals become very hot, which results in deterioration and breakage of the copper lead wires connecting the element to the switch.

To produce a tubular range element in which the reflector plate is readily removable for cleaning purposes, it is necessary so to arrange the tubes that their ends are located adjacent the edge of the unitary element and are bent downwardly through a cut out opening in the reflector plate adjacent its edge. The ends of the tubes, which may be directed straight downwardly or downwardly and slightly outwardly (away from the heat), are usually passed through a terminal shield or cup, which is intended to protect the terminals against overflowing liquids, but which in many instances fails to accomplish this important function.

An object of the present invention is to provide a unitary range element of the tubular type wherein the terminals are located in such a position that they are substantially unaffected by heat and overflowing liquids, wherein the reflector plate may be readily and quickly removed for cleaning purposes, wherein the entire unitary element may be conveniently detached from the range by an unskilled person, wherein a burnt out tube member may easily be replaced in the field, without disturbing the other parts of the element and without tools other than a simple tool such as a screwdriver, and wherein there is provided an improved but inexpensive and efficient supporting means for the tube members.

2

The invention will be described with particular reference to the accompanying drawing, in which

Figure 1 is a plan view of a heating element in accordance with the invention, as detached from a range structure,

Figure 2 is a sectional elevation of the heating element as located in a range structure and including a terminal box,

Figure 3 is a top view of the terminal box,

Figure 4 is a bottom view, partly in section of the terminal box,

Figure 5 is a side elevation, partly in section, of the terminal box,

Figure 6 is a sectional view of a terminal box detail,

Figure 7 is a partial sectional view of the heating element showing a modified form of clamping means, and

Figure 8 is a partial plan view of the clamping means shown in Figure 7.

While the element may comprise one or more tubular members, it is usual to provide two such members. Two tubes are illustrated in the form shown in the drawing, 1 being an outer tube in circular form, and 2 being an inner tube having a plurality of bends and curved portions. Such a tube arrangement provides a unit with the desirable "hot center," that is, the element may be economically used on medium load with small cooking vessels. The tubes contain the usual resistance member 4. A support 3, usually known as a spider, having four radially extending arms, as shown, is provided for the tubes. Spiders of this type have heretofore generally been formed of steel with portions thereof partially embracing the tubes to hold the latter in position. In accordance with one feature of the invention, the spider may be formed of cast iron, each arm thereof having a rib 5 extending along its upper surface with tube-supporting piers 6 formed thereon. The upper surface of the piers 6, on which the tubes rest, must of course be located in the same plane, this being preferably accomplished by submitting these surfaces to a simple grinding operation whereby all such surfaces are simultaneously ground to the same level.

Means for clamping the tubes firmly in position on the spider but for convenient and rapid detachment therefrom, when desired, comprises a clamp 7 positioned adjacent the end of each arm of the spider. Each clamp consists of an outer U-shaped clip or saddle 8 adapted to receive the tubes and an inner U-shaped clip 9. As shown, the inner clip fits within the outer clip, a portion of tube 1 being engaged by the

spaced arms of the clips at one side while a portion of tube 2 is engaged by the spaced arms of the clips at the other side. The edge of each arm of clip 9 is preferably flared outwardly, as indicated at 10, to fit around the sides of the tubes and thereby provide a firm fastening means for the same. The clips are mounted on a boss 40 formed on the spider, and a screw 11 secures the same thereto. It will be observed that, with the screws of the various clamps in tightened position, the two tubes will be held firmly on the spider. However, either tube may be readily slipped out of its seats in the clamps and separated from the spider simply by loosening the four screws 11 without, however, entirely removing such screws. Thus, no part of the clamp need be completely removed from the assembly and danger of loss of parts is avoided. The clips 8 and 9 and screws 11 are preferably formed of stainless iron to resist rusting.

Referring to Figures 7 and 8, an alternative means is there illustrated for clamping the tubes to the spider. Instead of the saddle 8, a pair of upright pins 36 are provided to engage the sides of the tubes. The pins 36 are securely fixed in bosses 37 formed on the spider, as by driving them into tight-fitting holes bored in the bosses. Instead of the clip 9, a cup-shaped member 38 is preferably employed. This cup 38 has an outwardly flared edge 38' to provide snug engagement with the upper wall portions of the tubes. The clip 38 is mounted on a boss 39 formed on the spider, and a screw 41 secures it thereto. A disc or washer 42 is preferably provided on the screw below the clip. This disc is mounted in fixed relation on the screw whereby the clip is always held in engagement with the head of the screw. Thus, when loosening the screw, the clip follows upward movement of the head thereof and disengagement of the tubes from the clamp is facilitated. Since the clip is cup-shaped, rotation thereof does not affect its clamping position. Moreover, since the upper surfaces of bosses 37 and 39 are in the same plane as those of piers 6, a single grinding operation only is required to level all these upper supporting surfaces of the spider. In the form shown in Figure 2, for instance, a second grinding operation would be required to level the supporting surfaces of bosses 43, which are in a different plane from that of the upper surfaces of piers 6.

The element assembly is suspended from the main frame 12 of the range by means of an annular frame 13, which also supports the reflector plate 14.

It will be observed that the four ends of the tubes are located in adjacent relation. As shown, these ends, indicated at 15, are firstly bent downwardly to extend through a cut out opening 16 in the reflector plate. The ends are then bent in an upward and outward direction, as clearly shown in Figure 2, whereby the extremities thereof are located substantially entirely beyond the periphery of the element. With the ends in this position, they are completely out of range of liquids overflowing on the element as well as of high temperatures of destructive range to the terminals and associated parts. It thus becomes feasible to employ terminals of the plug-in type in such a structure. Terminals of this type are of little practical use when exposed to considerable heat or to even a small amount of overflowing liquid, since the resulting sticking of the terminal pins in the socket makes disconnection difficult if not impossible.

The ends of the tubes are therefore preferably provided with plug-in type terminal pins 17.

The terminal box illustrated comprises a porcelain block 18 having a sheet metal housing 19 providing protecting back and two side walls for the block.

Means for clamping the tube ends to the housing comprise a U-shaped bracket 20 having its body portion fixed to the housing wall immediately below the porcelain block. Four aligned openings 21 are provided in either arm of the bracket and through such openings the four tube ends project. A bar 22 positioned between the arms of bracket 20 engages one side of each tube. A pair of clamping screws 23 extend through the bar and have square nuts 24 each of which fits between and engages a pair of tube ends adjacent their other sides. It will be observed that tightening of the screws will firmly secure the tube ends to the housing while loosening of the same will render it possible to withdraw the ends. In this clamping means also, it is not necessary wholly to remove any of the parts thereof from the assembly during the loosening and tightening operations thereof.

The terminal pins 17 are adapted to enter sockets 25 formed in the metal members 26, which are housed in the terminal block, as shown. Each member 26 may be square in cross-section, as illustrated in Figure 6, its lower portion being preferably split, as shown. The usual insulation-covered copper lead wires 27 are connected to the upper ends of the members 26. These lead wires are clamped firmly to the block by means of the U-shaped clamping bar 28 with clamping screw 29.

Since the terminal pins may be difficult to withdraw from their sockets, especially if they have remained therein for a long period of time, means are preferably provided to ensure easy manual withdrawal of such pins. This means comprises a lever 30 having a pair of arms 31 adjacent to and pivoted to the side walls of the housing 19 by means of the shaft 32. An operating bar 33 connects the two arms. The arms have forwardly extending portions 34 which fit into respective recesses 35 in the ends of the porcelain block. The upper edge of each portion 34 engages the upper side wall of the recess 35, as clearly shown in Figure 5, the operating bar 33 being thereby positioned angularly with respect to the back wall of the housing. It will be observed that, by grasping the bar 33 and back wall of the housing and pressing them towards each other, the porcelain block will be moved relatively to the housing whereby the pins will be withdrawn from their sockets.

There has thus been provided a range element with terminals so arranged that they are not subject to injury by overflowing liquids or excessive heat. Moreover, the arrangement described lends itself to the efficient use of plug-in type of terminals. The entire element may be quickly and conveniently removed from the range by any person without the use of tools, should it be found necessary to forward the same to a repairing establishment. On the other hand, either or both of the tubular members may be quickly replaced in the field simply by loosening the four screws 11 and the two screws 23.

The reflector plate may be readily removed for cleansing purposes by slightly lifting the right hand side of the element (with the spider) from the frame 13, whereupon the reflector may be slid out. It will be realized that this slight lifting of

one side of the tube unit will also cause the terminal block to move slightly during this operation. However, this movement will not impose any strain on the copper lead wires 21 because of their firm attachment to the block by means of the clamp 28, 29.

It will be understood that various changes in the details described may be made without departing from the spirit and scope of the invention as defined in the appended claim.

I claim:

In a plug-in type of electric range element having at least one tubular member, a terminal block comprising a substantially inclined porcelain block, a metal housing on the porcelain block, and means for clamping the ends of said tubular member to the housing comprising a U-shaped member having a body portion fixed to the housing and a pair of spaced arms having aligned openings therein to receive said ends,

5 a bar positioned between said arms and engaging one side of said ends, and a screw having a head engaging said bar and a nut thereon engaging the substantially opposite side of said ends.
